UNITED STATES PATENT OFFICE.

FRED N. MARTIN, OF PORTLAND, OREGON.

DESIGN FOR A REFRESHMENT BOOTH.

Application filed October 12, 1927. Serial No. 23,725. Term of patent 7 years.

To all whom it may concern:

Be it known that I, FRED N. MARTIN, a citizen of the United States, residing at Portland, in Multnomah County, and State of Oregon, have invented a new, original, and ornamental Design for a Refreshment Booth, of which the following is a specification, reference being had to the accompanying drawing, forming a part thereof.

Fig. 1 is a front view of a refreshment booth showing my new design, and Fig. 2 a side view thereof.

I claim—

The ornamental design for a refreshment booth as shown.

FRED N. MARTIN.
